(57) **CLAIM**

The ornamental design for a plane, as shown and described.

DESCRIPTION

FIG. 1 is a front perspective view of a plane, showing my new design.

FIG. 2 is a rear perspective view of the plane of FIG. 1.

FIG. 3 is a front elevation view of the plane of FIG. 1.

FIG. 4 is a rear elevation view of the plane of FIG. 1.

FIG. 5 is a right-side elevation view of the plane of FIG. 1.

FIG. 6 is a left-side elevation view of the plane of FIG. 1.

FIG. 7 is a top view of the plane of FIG. 1; and,

FIG. 8 is a bottom view of the plane of FIG. 1.

The broken lines in the drawings depict portions of the plane that form no part of the claimed design.

1 Claim, 8 Drawing Sheets
